PAPER WEIGHT

Lawrence R. Ervin, Sciotosville, Ohio

Application October 12, 1955, Serial No. 38,334

Term of patent 14 years

(Cl. D74—12)

Fig. 1

Fig. 2

Fig. 3

I claim:

The ornamental design for a paper weight, as shown.
